Inventor.

UNITED STATES PATENT OFFICE.

JACOB G. SLATER, OF POUGHKEEPSIE, ASSIGNOR OF TWO-THIRDS TO JOHN F. BROWN AND JAMES H. SIMONSON, BOTH OF ALBANY, NEW YORK.

CAR-COUPING.

SPECIFICATION forming part of Letters Patent No. 352,581, dated November 16, 1886.

Application filed July 12, 1886. Serial No. 207,809. (No model.)

To all whom it may concern:

Be it known that I, JACOB G. SLATER, a citizen of the United States, residing at Poughkeepsie, in the county of Dutchess and State of New York, have invented certain new and useful Improvements in Car-Couplers; and I do hereby declare the following to be a full, clear, and exact description of the invention, such as will enable others skilled in the art to which it appertains to make and use the same.

My invention relates to car-couplers; and it consists in the construction and arrangement of the parts, which will be more fully hereinafter described, and definitely pointed out in the claim.

The object of my invention is to provide a coupler which is simple and effective in its construction, positive in its action, easily handled and operated, readily understood, and conveniently applied without the use of unnecessary mechanism. I attain these objects by the mechanism illustrated in the accompanying drawings, wherein like letters of reference indicate similar parts in the several views, and in which—

Figure 1 is a perspective view of my improved car-coupler. Fig. 2 is a longitudinal vertical section of the same with the coupling-pin in a locking position. Fig. 3 is a view similar to Fig. 2, showing the position of the coupling-pin in the act of coupling. Fig. 4 is a view similar to Fig. 3, showing the coupling-pin in an uncoupling position. Fig. 5 is a view in side elevation of the coupling-pin.

A indicates the draw-bar, having a draw-head, B, mounted thereon, which draw-head B is provided with a projection, B', cast integral with the top thereof. As in the ordinary form of draw-head an opening, b, is provided in the front thereof, which connects with the link-recess b', in which the link C has movement and rests in coupling.

The draw-head B is provided with a vertical slot, B², the front and rear walls, b² and b³, of which are formed with a series of indentations, b⁴, and projections, b⁵, which are connected by gradual curves. This slot B² is wider at its top than at its lower portion, and has suitable guard projections, b⁶ and b⁷, respectively, at the top of the front and rear walls, b² and b³.

A reversible coupling-pin, D, having indentations d and projections d' corresponding to and engaging with the indentations b⁴ and projections b⁵ of the slot B², engages with the said slot, assuming the several positions shown. This pin D is provided with a stem, d², which has a ball or other suitable handle, d³, cast therewith. The bottom portion of this pin D is V-shaped, as at d⁴, its lower end being formed blunt and gradually curved. This portion of the pin fits in the lower portion of the slot B², which conforms to the shape of the said pin at this point.

The rear portion of the link-recess b' is enlarged and formed with a series of indentations, 1, 2, and 3, for the reception of the end of the link C in the positions it assumes in coupling with cars of different grades and as an aid for the action of the coupling-pin D.

Extending transversely from either side of the slot B² are semicircular slots 4 and 5, which extend vertically through the draw-head and form a recess for the reception of a common coupling-pin in case the coupling-pin D should be broken by accident or otherwise.

A suitable cord or chain may be connected to the handle of the coupling-pin D, for slightly lifting it when it is adapted to uncouple the cars, which cord or chain may extend to one side of the car, or above the same, if necessary.

When the link D is fixed or coupled, it assumes the position shown in Fig. 2, its front edge engaging with the front wall of the slot B². In uncoupling, the pin D is slightly raised and the link C allowed to withdraw, the said link assuming the inclination shown in Fig. 3, the pin dropping down by gravity and remaining in an upright position. In coupling the link C strikes the lower V-shaped portion of the pin D, and the pin takes the oppositely-inclined position shown in Fig. 4. When the link C passes under the lower point of the pin D, the said pin drops down through the link-aperture and engages with the front wall of the slot B². When the link strikes the lower portion of the pin, the said pin is retained in the slot B² by striking the projecting guards b⁶ and b⁷, formed with the front and rear walls at the top of the slot B².

The pin D is constructed of a flat piece of metal of sufficient thickness as to just fit the

slot B², and has its edges formed of the same configurations as said slot, so as to be adapted to be reversed in case the one side should become worn by continual use.

5 This coupler can be constructed by suitable means, and is positive and effective in its action, dispensing entirely with gudgeons or wrist-pins, and depending entirely on the action of the pin itself to produce the desired result.

A means of safety is afforded in case of fire or accident both to traveling stock and operatives by the ease and readiness with which the link can be uncoupled in whatever position it may be placed.

The coupler can be cheaply manufactured, and is easily applied to any car now in use without any change in the form of mechanism commonly used.

15 20 It is obvious that slight changes in the construction and arrangement of the parts could be made and substituted for those shown and

described without in the least departing from the nature and principle of my invention.

Having thus described my invention, what 25 I claim as new, and desire to secure by Letters Patent, is—

As an article of manufacture, an improved car-coupler consisting of a vertically-slotted draw-head provided with indentations and projections in the front and rear walls, a reversible coupling-pin engaging with said slot and having projections and indentations conforming and adapted to engage with those formed in the front and rear walls of the vertical slots, 30 and a link-recess formed with a series of indentations in the rear walls thereof, substantially as described.

In testimony whereof I affix my signature in presence of two witnesses.

JACOB G. SLATER.
